UNITED STATES PATENT OFFICE.

PETER ZIELINSKI, OF PALATKA, MICHIGAN.

WINDOW-LOCK

1,252,528.

Specification of Letters Patent. Patented Jan. 8, 1918.

Application filed May 28, 1917. Serial No. 171,499.

To all whom it may concern:

Be it known that I, PETER ZIELINSKI, a subject of the Emperor of Austria, residing at Palatka, in the county of Iron and State of Michigan, have invented certain new and useful Improvements in Window-Locks, of which the following is a specification.

This invention relates to window locks and has special reference to a sash lock 10 adapted for use in connection with the sash of weightless windows.

One important object of the invention is to improve the general construction of devices of this character. 15 A second object of the invention is to provide an improved form of sash lock which can be readily thrown into or out of operation.

With the above and other objects in view, 20 as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:

Figure 1 is an inside view of a portion of 30 a window and frame showing a pair of the sash locks applied to the lower sash of the window.

Fig. 2 is an enlarged front view of one of the sash locks.

Fig. 3 is a section on the line 3—3 of 35 Fig. 2.

Fig. 4 is a side view of a lock on the scale shown in Fig. 2.

Fig. 5 is a section on the line 5—5 of 40 Fig. 2.

In the embodiment of the invention herein illustrated there has been shown in the drawings a base plate 10 whereon is eccentrically pivoted a disk 11, the pivot of the 45 disk being indicated at 12 and lying as shown above the horizontal line passing through the center of the disk.

Below this disk is a pair of ears 13 and 50 14 in a housing 15 provided with a slot 16, and slidably mounted in these ears is a plunger 17 having on its upper end an arcuate head 18 on which the disk rests. This head, lying flat against the base 10 prevents rota-

tion of the plunger. Mounted on the plunger is a pin 20 provided with a head 21. 55 This pin passes through the slot 16 and its head forms a finger grip. In order to normally hold the disk in operative position a spring 22 surrounds the plunger between the head and ear 13 and constantly urges the 60 plunger upward.

From the foregoing it will be seen that the spring presses the plunger upward so that the disk acts as a cam. Under these circumstances the window sash may be raised 65 and when released from the hands of the operator its downward movement will be prevented by the cam action of the disk. However, if it be desired to lower the window it is simply necessary to depress the 70 pins by gripping the finger pieces. Then if the window be slightly lifted the disks will drop on to their seats free from the side of the window frame, with which they generally engage, and the window can be 75 lowered at will.

There has thus been provided a simple and efficient device of the kind described and for the purpose specified.

It is obvious that many minor changes 80 may be made in the form and construction of the invention without departing from the material principles thereof. It is not therefore desired to confine the invention to the exact form herein shown and described but 85 it is wished to include all such as properly come within the scope claimed.

Having thus described the invention, what is claimed as new is:

1. In combination, a base, a disk eccentrically pivoted on said base and adapted to engage against a portion of the side of a window frame, the center of said disk being below its pivot point, a plunger bearing against the underside of said disk, a spring 90 arranged to urge the plunger yieldably upward and thereby lift the disk, and means to permit holding of the plunger in its lowered position whereby to permit dropping of the disk out of contact with the said 95 frame portion.

2. In combination, a disk eccentrically pivoted on said base and adapted to engage against a portion of the side of a window frame, the center of said disk being below 100 the pivotal point thereof, a pair of ears on

said base below said disk, a housing covering the ears and having a vertically disposed slot therein, a plunger slidably mounted in said ears and having an arcuate head on which said disk rests, a headed pin carried by the sleeve and projecting through the slot, a finger grip fixed below the head

of the pin, and a spring surrounding the plunger and urging it upward.

In testimony whereof I affix my signature.

PETER ZIELINSKI.
